DEVICE FOR DISPENSING LIQUIDS, GRANULATED PRODUCTS, AND THE LIKE

Filed Jan. 25, 1939

UNITED STATES PATENT OFFICE

2,187,927

DEVICE FOR DISPENSING LIQUIDS, GRANULATED PRODUCTS, AND THE LIKE

Joseph Rene Ayotte, Chicago, Ill.

Application January 25, 1939, Serial No. 252,758

4 Claims. (Cl. 65—31)

(CL 65-31)

This invention relates to improvements in devices for dispensing liquids, granulated products and the like.

In pouring liquids from a container, particularly where the liquid is of a viscous character, a sudden cut off of the flow of liquid is desirable in order that a definite quantity may be poured and also to prevent the liquid from dripping down the side of the container when the pouring operation is being completed, as when the container is being righted. Generally the dispensing devices now in use require a downward pressure of the thumb to operate the elements of the device to permit the flow of liquid. It is found that when the container is grasped in the hand for pouring it is inconvenient and awkward to exert a downward pressure with the thumb to cause the device to open so that the contents may be poured, the natural tendency being to exert a forward pressure with the thumb.

In accordance with the foregoing, it is therefore an object of this invention to provide a dispensing device in which the actuating member is pushed forwardly with the thumb in line with the natural tendency of the operator to thereby effect the operation of my device.

30 A further object of my invention is to provide a dispensing device having a slidable cover which is pivotally mounted so as to be movable in a substantially arcuate direction to open and close the spout opening.

35 A further object of my invention is to provide a dispensing device which effects a tight seal with the spout opening to prevent accidental spilling of the contents and the entrance of foreign matter when same is closed.

A further object of this invention is the provision of a dispensing device which can be kept sanitary and easily cleaned.

40 A still further object of this invention is the provision of a dispensing device of the character described which is simple in construction, efficient in operation and economical to manufacture.

45 Other objects will become apparent as this description progresses.

50 In the drawing wherein like reference characters denote corresponding parts through the several views:

Fig. 2 is a plan view of the device shown in

55 Fig. 1. Fig. 3 is a cross sectional view taken on line 3-3 of Fig. 2.

Fig. 4 is a plan view with the cap of the device removed showing the operating mechanism in normal closed position.

Fig. 5 is a similar view showing the positions assumed by the parts during operation of the mechanism.

Fig. 6 is a fractional cross sectional view taken on line 6-6 of Fig. 1.

Fig. 7 is an enlarged fractional cross sectional view taken on line 7-7 of Fig. 2.

Fig. 8 is an enlarged fractional cross sectional view taken on line 8-8 of Fig. 4.

Fig. 9 is a plan view of the cap looking in the directions of the arrows 9-9 of Fig. 1.

Fig. 10 is a perspective view of a detail.

In the drawing, wherein is shown a preferred embodiment of my invention the numeral 20 designates a body portion which is provided interiorly thereof with screw threads 22 which are adapted to engage corresponding threads 24 on the mouth of a container 26 and by means of which the body portion 20 is secured thereon. An angularly inclined spout 28 is formed forwardly of the body portion 20 and is provided with an aperture 30 through which liquid or other material may pass. Integrally formed with the body portion 20 is a handle 32 which is provided with a recess 34 adjacent the juncture of the handle and body portion, said recess being adapted to receive the member 36 shown in Fig. 10 and presently to be described. Vertical ribs 37 are spacedly disposed on the periphery of the body portion 20 and serve to strengthen the peripheral wall 21 as well as to enhance the gripping surface for tightening or loosening the device on a container. Bosses 38 are provided on the top surface of the body portion 20 and are drilled to accommodate the resilient friction elements 40 which are imbedded in the cap 42 and which serve to frictionally secure the cap 42 on the body portion 20. A rivet 39 is imbedded in the surface of the body portion 20 and is partly retained in an embossed portion 41 formed on the surface said embossed portion forming a shoulder for the member 60 presently to be described. An aperture 44 adapted to serve as an air vent is additionally provided in the top surface of the body portion 20.

The member 36, shaped substantially as shown in Fig. 10, is provided with a horizontally extending bore 46 which serves to receive the slideable element 48 presently to be described. The member 36 is tapped to receive a screw 51 which is adapted to secure same in the recess 34 of the handle 32. 45 50

The slideable element 48 comprises a tubular body portion 50 closed at one end and provided at the other end with an extension 52 having a terminal portion 53 which terminates in angular relationship with the tubular body portion 50. As shown in Fig. 3, the terminal portion 53 is offset with respect to the surface plane of the extension 52. The extension 52 is provided with

an embossed or raised portion 54 which serves as a stop for the slidable member 48. An aperture 56 formed in the extension 52 is adapted to register with the aperture 44 to provide an air vent in the device to facilitate the pouring of liquids. A slot 58 substantially V shaped is provided in the terminal portion 53 of the extension and is adapted to receive a pin or rivet 59 mounted on the member 60.

10 The member 60 is pivotally mounted as at 61 on the rivet 39 and is adapted to serve as a cover for the spout 28. The rearward portion of the member 60 is slightly offset as shown in Figs. 3 and 8. It is adapted to ride on the shoulder of 15 the boss 41 so as to permit the forward portion of the member 60 to fit snugly against the top of the spout 28 and to close effectively the aperture 30.

A coil spring 62 contained in the tubular body 20 portion 50 abuts the peripheral wall 21 and serves to keep the tubular body portion 50 in normal out position with the member 60 directly over the aperture 30 of the spout 28 and closing same as shown in Fig. 4. It will be seen that 25 in this position the embossed portion 54 of the extension 52 abuts the member 36 and serves as a stop to prevent further movement to the right of the slidable element 48.

When it is desired to pour from the container 30 the device is grasped by the handle 32 and pressure is exerted with the thumb against the tubular body portion 50 to push the slidable member 48 to the left. It will be seen that the thumb is always uppermost when a vertically extending 35 handle is grasped by the hand and that the natural tendency is to press forwardly with the thumb, particularly when the container is being tilted as for pouring. To exert pressure with the thumb in any other direction would be extremely awkward and inconvenient. As the slid- 40 able member 48 moves to the left the pivotally mounted member 60 is caused to be rocked about its pivot 61 to assume the position shown in Fig. 5. In this position the opening 30 in the spout 28 is uncovered to permit the free flow of liquid 45 therethrough. When the thumb is removed from the tubular body portion 50 the spring 62 acts to push the slidable member 48 to the right causing the member 60 to be rocked back to normal 50 position and effecting an instantaneous cut off of flow of fluid.

With this construction it is thus possible to keep the container effectively sealed when not in use, to control more effectively the quantity 55 of fluid to be poured and to eliminate dripping of the contents down the side walls of the container.

It is understood that the form of my invention, herewith shown and described, is to be taken as 60 a preferred example of the same, and that various changes in the shape, size and arrangement of parts may be resorted to, without departing from the spirit of my invention or the scope of the appended claims.

65 I claim:

1. A dispensing device of the class described comprising a body portion having a flat closure surface and a spout opening therein, a handle associated with said body portion, a horizontally disposed cover plate for said spout opening, said cover plate being pivotally mounted on said flat closure surface and arcuately movable on said flat surface over the top of said spout opening,

an actuating member slidably mounted with respect to said body portion and in engagement with said cover plate, spring means for urging said actuating member rearwardly to pivotally move said cover plate over the top of said spout opening to close said spout opening, said handle adapted to be grasped by the hand and the actuating member adapted to be pushed forwardly by the thumb to cause said cover plate to move in an arcuate direction to uncover the top of said 10 spout opening.

2. A dispensing device of the class described comprising a body portion having a flat closure surface and spout opening forwardly thereof, a handle disposed opposite said spout opening, a horizontally disposed cover plate for said spout opening, said cover plate being pivotally mounted on said flat closure surface, an actuating member in engagement with said cover plate, said actuating member disposed above said handle and adapted to be moved forwardly by pressure of the thumb of the hand when said handle is grasped by the hand, the forward movement of said actuating member causing said cover plate to move in an arcuate direction on said 20 flat closure surface over the top of said spout opening to uncover said spout opening, and spring means for urging said actuating member rearwardly to pivotally move said cover plate to normal closed position when the thumb pressure 30 is removed from said actuating member.

3. A dispensing device of the class described comprising a body portion and a handle associated therewith, said body portion having a flat top closure surface and a spout opening in said 35 closure surface, a horizontally disposed cover plate for said spout opening, said cover plate being pivotally mounted on said flat closure surface and arcuately moveable over the top of said spout opening, an actuating member disposed above said handle and slidably mounted with respect to said body portion, said actuating member having an extension in engagement with said cover plate, said actuating member operable by the thumb of the hand in a forward direction 40 when said handle is held in the hand to pivotally move said cover plate over the top of said spout opening to uncover and open same, and spring means for urging said actuating member rearwardly to pivotally move said cover plate over 50 said spout opening to cover and close same.

4. A dispensing device of the class described comprising a body portion having a top flat closure surface and a spout opening in said closure surface, a handle associated with said body portion and disposed opposite said spout opening, a horizontally disposed cover plate for said spout opening, said cover plate being pivotally mounted on said closure surface and pivotally movable over the top of said spout opening, an actuating member for pivotally moving said cover plate, said actuating member including a tubular portion having an extension in engagement with said cover plate, said tubular portion being engageable by the thumb of the hand when said 65 handle is grasped in the hand and being operable in a forward direction to pivotally move said cover plate over the top of said spout opening to uncover same, a spring retained in said tubular portion for urging said actuating member rearwardly, to pivotally move said cover plate over 70 the top of said spout opening to close same.

JOSEPH RENE AYOTTE.
